UNITED STATES PATENT OFFICE.

FRANK MADSON HENRY HEMPEL, OF PLATTSMOUTH, NEBRASKA.

CORN-PLANTER.

SPECIFICATION forming part of Letters Patent No. 357,199, dated February 8, 1887.

Application filed October 16, 1885. Serial No. 180,044. (No model.)

To all whom it may concern:

Be it known that I, FRANK MADSON HENRY HEMPEL, residing at Plattsmouth, in the county of Cass and State of Nebraska, have invented certain new and useful Improvements in Corn-Planters; and I do hereby declare that the following is a full, clear, and exact description thereof, reference being had to the accompanying drawings, making part of this specification.

My invention relates more particularly to corn-planters, but it can be applied with equal advantage to all classes of seed-planting machines; and it consists, principally, in the means employed for actuating the droppers or seed-valves by the rotary motion of the ground-wheel and the particular mechanism used to throw the same in and out of gear, the means employed to operate a cross-marker, and other minor improvements, hereinafter fully described.

In the accompanying drawings, Figure 1 is a longitudinal section through the center of the planter. Fig. 2 is a back view showing one wheel in part section. Fig. 3 is a plan. Figs. 4, 5, 6, and 7 are details.

The frame A, A', and A² is mounted upon and secured to the axle B and the cross-piece C. The ground-wheels E E' are journaled upon the end of the axle B, and the droppers F F' are supported at each end of the cross-piece C. The bar D, to which is rigidly attached the pole D' and the rod d d', is hinged to the forward ends of the bars A A'. The rod d is connected to the lever G by the rod d'. The lever G is fulcrumed at g', and has foot-plate g. It will be seen that by pressing the foot-plate g down the forward end of the frame A A' will be raised. The catch g' engages the lever G when pressed down.

A marker, H, is pivoted at h to the bar A² of the frame. This marker is braced by the rod I. The curved rod i' is secured at each end of the bar D and arches over the same. An eye is formed on the end of the brace-rod I, through which the guide-rod i' passes, so that in throwing the marker H over from one side of the planter to the other the brace-rod I follows along the guide-rod i'. The spring-50 catch h' holds the marker H in a perpendicular position when not in use.

Attached to the hub of the ground-wheel E is a disk, k, to which is secured the ratchet-wheel K. The disk L revolves freely on the face of disk k, and has an open center which allows the ratchet-wheel K to protrude above the face of disk L. This disk or ring L has two arms, l l', which are provided with studs l' l'. Pivoted to this disk L is a pawl, l², which is made to engage with ratchet-wheel K, and is held in connection with the ratchet-wheel K by the spring l³, so that as the ground-wheel E revolves, in drawing the planter along, the disk L, with arms l l' and studs l' l', revolve also, while the pawl l² is in connection with the ratchet-wheel K. When the pawl l² is thrown out of connection with the ratchet-wheel K, the disk L remains still, while the ground-wheel E rotates. Now, as the studs l' l' on the arms l l' of the disk L operate the droppers and also a cross-marker while revolving with the ground-wheel E, it will be seen that by disengaging and engaging the pawl l² with the ratchet-wheel K the planter is thrown in and out of gear when desired.

In the disk L an oblong hole, m², is cut. Through this hole, and pressing against the outside of the arm of pawl l², is a stud, m'. The arm of pawl l² is so formed at the end that as the stud m' moves along the oblong hole m² it throws the pawl l² out of connection with the ratchet-wheel K. The stud m' is secured to a circular strip, m³, which moves in a shallow groove cut on the underneath side of disk L, the ends of which are turned out and form the arms m m, so that while the disk L is revolving with the ground-wheel E, if either of these arms m m is pressed toward the arms l l' of the disk L the pawl l² will be disengaged with the ratchet-wheel K and the disk L will remain still, while the ground-wheel revolves.

Now, it will be seen that the droppers and cross-marker are operated automatically as the planter is drawn across the field by the rotary motion of the ground-wheels E, and that by throwing out the bar N against either of the arms m m the pawl l² will be disengaged from the ratchet-wheel K, and the ground-wheel E will revolve without operating either the droppers or cross-marker. The bar N (see Fig. 2) moves in the guide n', which is secured to the frame of the planter. The studs n² n³ prevent

the bar N from moving in or out more than is required. The lever n^3 moves the bar N, and is arranged so that it can be operated by the driver.

- 5 On the outer edge of the disk L, and at right angles from the center of the wheel with the arms $l^1 l^2$, are short ratchets $o^1 o^2$. A pawl, o' , is hinged to the plate o^2 , over and in line with these short ratchets. The plate o^2 is secured 10 to the frame B of the planter. The pawl o' engages the ratchet o and prevents any backward motion of the disk L. This also holds the disk L in such a position that the cross-marker P is held up from the ground while 15 turning round, backing, and getting the machine in position for planting. (See Fig. 7.) As soon as the bar N is drawn away from the arm m and the machine begins to move forward, the cross-marker is let down and at the 20 same time a hill of corn or other seed is dropped from the seed-tube to the ground.

The cross-marker P, braced and hinged with the rods $p^1 p^2$, is raised and lowered by the rod p' . The shaft p^2 is journaled by two eyebolts secured 25 to the axle-bar B and has its ends turned at right angles at each end, forming crank-arms p^3 and p^4 . To the arm p^3 is hinged the rod p' . The crank-arm p^4 is in line with the studs $l^1 l^2$, so that as the disk L revolves with the ground- 30 wheel E the stud l^1 , projecting from the disk-arm l, comes in contact with the crank-arm p^4 and depresses it, which raises the cross-marker P from the ground. The stud l^1 retains the arm p^4 for a part of its revolution, when it is released and the marker P drops to the ground. 35 In this way the two studs $l^1 l^2$ alternately raise the cross-marker P from the ground. The arm p^4 is released by the stud l^1 a little before the arm R, which operates the droppers. This 40 brings down the cross-marker P upon the ground a little before the hill of corn is dropped. It is then allowed to drag along the ground a short distance before it is again raised up by the stud l^1 . This makes a slight furrow or 45 mark between each hill of corn as it is planted, and allows the operator to see distinctly the rows of hills as he is planting, and allows him to correct any tendency to get out of line. In crossing ditches it is sometimes necessary to 50 throw the planter out of gear, and being able to distinctly see where he has already planted, it is an easy matter to line up with these cross-marks when commencing to plant again.

I am aware that corn-planters have been 55 patented which operate the dropping devices by the rotary motion of the ground-wheels, and I attribute a good deal of their non-success to the fact that in operation there is no mark or anything to show where the seed has 60 been planted. In crossing a ditch or any unevenness of the ground will throw the rows out of line. This is also the case in using the "check-rower" now in use; but where a distinct mark is made between each hill as it is 65 planted it is an easy matter for the operator to correct any unevenness in the rows and line

up with the marks made where he has already planted.

The bar N holds the disk in such a position, so that as soon as it is drawn away from the arm m a hill of corn is dropped as soon as the planter is started, as shown in Fig. 7.

The droppers are operated by two pivoted arms, R and S, pivoted at r^1 and s^1 , and connected by rods r^2 and s^2 . (See Fig. 4.) The 75 studs $l^1 l^2$, in revolving with the ground-wheel E, depresses the arm R, as shown by dotted lines of Fig. 4, which draws over rod r^2 . The arm S, being pivoted at s^1 , throws rod s^2 in the opposite direction. As soon as the arm R is 80 released the counterbalance-ball s^3 , which is attached to the shaft T, raises the arm R to its original position. The arms $s^2 s^3$ are connected by the shaft T, which operates both droppers F F at the same time. S:

The seed-tubes U have two hinged valves, $u^1 u^2$, which are hinged a little distance from the sides of the tubes. The arm V is pivoted in the center, and has two studs, v^1 and v^2 , projecting and placed under each of the hinged 90 valves $u^1 u^2$. It will be seen that when a reciprocating motion is given to the rod V the valves $u^1 u^2$ will be alternately opened and closed, thus always retaining a hill of corn ready to be dropped in the bottom of the seed-tube U. As the arm R is depressed the lower valve, u^2 , of the seed-tube is opened and the upper one is closed, and the required quantity of seed is dropped from the dropper device onto the upper valve, u^1 . As soon as the 100 arm R is released the lower valve, u^2 , is closed and receives the seed dropped from the upper valve, u^1 , which is then opened.

The dropping-disk Y receives its rotary motion from the reciprocating motion given to the disk X with an arm, x^1 , the end of which is turned up and hinged to the end of rod s^2 . The rotary dropping-disk Y has a circular ratchet formed on its underneath side. The disk X, which is placed directly under this, contains a spring-pawl, x^2 , arranged so as to engage in the tooth of ratchet on dropper-disk Y. The disks Y and X rotate from the same center. The disk X has another arm, x^3 , which operates the pivoted arm V in the seed-tube U, so that the reciprocating motion given to the disk X through the arm x^1 rotates the seed-dropping disk Y, and also imparts a reciprocating motion to the arm V through the arm x^3 , and which opens and closes the seed-valves u^1 and u^2 at the same time that the seed-dropping disk Y drops the seed into the seed-tube U.

The furrowing shoe or runner is made detachable from the seed - dropping hoppers, which is an advantage in making repairs, &c.

The ground-wheels E E' have two corrugations, $e^1 e^2$, formed on their face toward the outer edge of the wheel. A wheel for planters formed in this way has two advantages as a means of pressing the earth over and covering the seed as it is planted—first, the wheel having a flat plain surface, the earth is evenly and well

pressed over the seed; secondly, the corrugations being at each side of the wheel and also at each side of the hill of seed planted, prevents the earth from slipping away, as would be the case if the wheels were flat and without the corrugations.

This machine for planting corn requires only two arms, $l l$, on the disk L , the ground-wheel being of the proper diameter; but for drilling 10 corn and other seed in rows it will be necessary to use a disk with a greater number of arms—six or more, according to the diameter of the ground-wheel—and to remove altogether the cross-marker and attachments. For drilling 15 wheat and other small grain the required number of dropping devices can be arranged in a longitudinal hopper in front of the planter, and arms extending from the shaft T operating each dropper.

Having fully described my invention, what I

desire to secure by Letters Patent, and claim, is—

1. In a corn or other seed planting machine, the combination of an adjustable seed-tube, U , with arm Y , valves $u u'$, studs $v v'$, for the purpose set forth and described. 25

2. In a corn-planter or other seed-planting machine, the combination of the ratchet-wheel K , disk L , arms $l l$, studs $l' l'$, pawl l' , spring l^2 , the circular strip m^3 , arms $m m$, arms R and S , and connecting-rods r and s , the shaft T , crank-arms $s^2 s^2$, with the disk X , having a spring-pawl, x' , arms x and x^2 , and stud x^2 , for the purpose of operating the seed-dropping disks and seed-valves u and u' , fully described 35 and set forth.

FRANK MADSON HENRY HEMPEL.
